UNITED STATES PATENT OFFICE.

ARTHUR P. CURTIS, OF ITHACA, NEW YORK, ASSIGNOR TO ITHACA GUN COMPANY, OF ITHACA, NEW YORK, A CORPORATION OF NEW YORK.

BOLTING MECHANISM FOR GUNS.

1,348,545.

Specification of Letters Patent.

Patented Aug. 3, 1920.

Application filed May 17, 1919. Serial No. 297,812.

To all whom it may concern:

Be it known that I, ARTHUR P. CURTIS, a citizen of the United States of America, residing at Ithaca, in the county of Tompkins and State of New York, have invented certain new and useful Improvements in Bolting Mechanism for Guns, of which the following is a specification.

The primary object of my invention is 10 the provision of means in the nature of a gun barrel lock, for maintaining a gun action securely closed during the firing operation, and readily releasable for opening whenever desired.

15 A further object of my invention is to provide bolting means for the frame and barrel of a gun, transversely of the latter, shiftable to and from its locking position by means of substantially the usual form 20 of top lever.

A still further object of my invention is the provision of a gun action having substantially the usual appearance when closed, provided with a suitable form of 25 transversely positioned bolt readily locking the frame and barrel together when the action is closed, the top lever serving to readily shift the bolt to its locking or unlocked position.

30 With these general objects in view my invention consists of the basic idea of bolting two barrel extension lugs to a gun frame or body with one bolt set at a right angle to the axis of the bore of the barrel and 35 the novel construction, combination and arrangement of parts hereinafter more fully described, illustrated in the accompanying drawings, and then claimed.

In the drawings forming a part of this 40 application and in which like reference characters designate corresponding parts throughout the several views.

Figure 1 is a side elevation of a portion of a gun with the action closed and the 45 barrel securely bolted to the frame or body.

Fig. 2 is a similar view in its open position,

Fig. 3 is a perspective view of a portion 50 of the breech end of the barrel illustrating my locking means with the bolt partially broken away and parts removed,

Fig. 4 is a top plan view of Fig. 1,

Fig. 5 is a similar view with the locking bolt retracted and the barrel extensions released ready to open the action,

Fig. 6 is a top plan view of the bolt operating portion of the top lever,

Fig. 7 is a top plan view of the top lever articulated with the locking bolt and

Fig. 8 illustrates top and rear sides and 60 the opposite ends of the bolt.

Referring more in detail to the drawing, a portion of a gun is illustrated with the frame 10 and barrel 11 hinged together by a pivot or hinge pin 12 in the usual manner, the barrel being provided with a fore end iron 13 with a tip or fore end of wood 14 while the stock 15 rearwardly extends from the action frame or body 10.

The breech end or rear face 16 of the 70 barrel 11, is provided with parallel lugs or extensions 17 and 18 adapted for closely fitting within correspondingly shaped grooves 19 and 20 respectively in the adjacent face 21 of the body 10, when the faces 75 16 and 21 are closely fitted together in abutting engagement with the gun action closed. An elongated bolt 22 slidable transversely of the body 10 in a correspondingly shaped socket 23 in the body freely receives a forward extension 24 of the top lever 25 within a longitudinal slot 26 of the bolt, whereby the bolt is manually shiftable at right angles to the axis of the bore 15.

The top lever 25 is pivoted in the top 80 of the body 10 in the usual manner, such as by a hub 27 attached to the bottom of the lever, it being apparent that the bolt 22 being normal when the lever 25 is longitudinally positioned as shown in Figs. 1 85 and 4 of the drawing, the manual shifting of the lever 25 to its extreme right-hand position, forcibly retracts the bolt 22 as shown in Figs. 2 and 5 thereof.

The inner end of the bolt 22 is beveled or 90 tapered as at 28 adapted for reception within a correspondingly tapered keeper opening 29 in the extension lug 18 when the bolt is in its locking position. The lug 17 is provided with a recess 30 through which the 100 bolt 22 is slidable during operation when the action is closed, with the lug 17 seated in the groove 19. A side notch 31 in the bolt 22 permits the lug 17 to pass through said notch for opening the action when the 105 bolt 22 is projected in its released position as will be evident from Fig. 5 of the drawing.

The complete operation of my invention will be apparent from this detailed descrip- 110

tion thereof, it being understood that when the top lever 25 is centrally positioned upon the stock 15 and tang of the frame 10, Fig. 4, and the bolt 22, with the barrel 11 closed, 5 is in its locked position, extending through the recess 30 of the lug 17 at an unbroken portion of the bolt, while the tapered end 28 thereof is seated in the opening 29, of the extension lug 18.

10 The shifting of the top lever 25 in the usual manner to open the gun action, projects the bolt 22 outwardly of the socket 23, sufficiently to bring the notch 31 in alignment with the lug 17 and the end 28 out 15 of the opening 29, whereby the barrel 11 and body 10 may be relatively moved upon the hinge pin 12 and the action opened, as illustrated in Fig. 2. A cylindrical form 20 of bolt 22 is herein illustrated it being understood, however, that my invention contemplates any desired form of bolt, such as one that is angular in cross section and although the preferred construction of the invention is set forth, minor changes may 25 be made therein without departing from the spirit and scope of the invention as claimed. The invention is readily adaptable for different kinds of guns having the opening and closing action, the top lever 25 being 30 furnished with the usual construction of automatic trip for retaining the lever as well as the bolt 22 released until the barrel 11 and body 10 are manually closed.

I claim:-

- 35 1. A gun comprising pivotally connected body and barrel portions, a bolt transversely shiftable within said body portion having a side notch and a tapered inner end, extensions upon said barrel portion having a keeper recess and tapered opening adapted 40 for receiving a side portion and the pointed end of the bolt, when the bolt is in its retracted locking position, the tapered end of the bolt when in its projected released position being out of the adjacent path of 45 travel of one of said extensions, with the notch opening at the other of said grooves in the path of travel of the other extension.
2. In a gun having hingedly connected 50 body and barrel the engaging faces of which are respectively provided with grooves and keeper extensions adapted for reception

therein when the gun is closed, one of said extensions having a keeper opening and the other having a keeper recess in axial alignment with said opening, a bolt transversely slid able in said body, positioned in said recess and opening at one extremity of its movement, the said bolt having a side notch adapted for the free movement of one of 60 said extensions therethrough, when the bolt is at the other extremity of its movement with its inner end spaced from the path of travel of the other extension.

3. A gun comprising pivotally connected 65 body and barrel portions, one of said portions being provided with a pair of spaced recesses, the other of said portions being provided with a pair of extensions adapted 70 to be received in said recesses, one of said extensions having a recess formed in the outer edge thereof and an opening formed in the other extension spaced from the edges thereof, and a bolt slideable transversely of the part in which said recesses are formed 75 adapted when moved in one direction to extend into said extension opening and partially into said extension recess to prevent pivotal movement of the connected body and barrel portions.

4. A gun comprising pivotally connected 80 body and barrel portions, one of said portions being provided with a pair of spaced recesses, the other of said portions being provided with a pair of extensions adapted 85 to be received in said recesses, one of said extensions having a recess formed in the outer edge thereof and an opening formed in the other extension spaced from the edges thereof, a bolt slideable transversely of the 90 part in which said recesses are formed adapted when moved in one direction to extend into said extension opening and partially into said extension recess to prevent pivotal movement of the connected body and 95 barrel portions, said bolt having a side notch therein adapted to register with the extension having the edge recess when the end of said bolt is removed from the extension opening to permit a pivotal separating movement 100 of the body and barrel portions.

In testimony whereof I affix my signature.

ARTHUR P. CURTIS.
